SVEN G. BOLIN, OF ROSEDALE, KANSAS.

METAL DOOR.

1,184,920.

Specification of Letters Patent. Patented May 30, 1916.

Application filed September 29, 1912. Serial No. 792,402.

To all whom it may concern:

Be it known that I, SVEN G. BOLIN, a citizen of the United States, residing at Rosedale, in the county of Wyandotte and 5 State of Kansas, have invented certain new and useful Improvements in Metal Doors; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to fireproof metal doors, and has for its principal object to provide a door of this class with means for receiving and securely holding a panel of glass or other material. In accomplishing this object I have provided improved 20 details of structure, the preferred forms of which are illustrated in the accompanying drawings, wherein:—

Figure I is a perspective view of a metal 25 door constructed according to my invention. Fig. II is an enlarged cross-section of one of the door stiles or rails, and a portion of a panel carried thereby. Fig. III is a detail perspective of a portion of the stile 30 or rail and its socket hooks. Fig. IV is a detail perspective of a portion of a panel socket adapted for application to the stile or rail, and for carrying a panel. Fig. V is a detail perspective of a portion of the 35 molding. Fig. VI is a cross-section of a stile or rail, showing a modified form of panel socket and molding.

Referring more in detail to the parts:— 1 designates the stile and 2 the rails of a 40 metal door, which, except for the improvements hereinafter described, may be of any ordinary construction. Each of the stiles and rails has its inner portion adapted for receiving a panel of glass or other suitable 45 material, and for carrying a molding which cooperates with the panel to enhance the appearance of the door, and as the construction for each of the stile and rail edges is the same, I will describe but one in detail 50 with the understanding that such description relates equally to all.

The material at the inner edge of the stile or rail is turned inwardly and thence outwardly to form a narrow channel 4 and 55 the ends of the material are bent backwardly to form a V 5, having a free outer member

6 spaced from the inturned body portion 7 and out-turned neck portion 8 to receive and lock coöperating members of a panel socket, the panel socket 10 comprising a U-shaped body 11, which is adapted for projection through the channel 4 into the neck of the door stile or rail, and has backturned free edges 12 forming a V of about the same angle as the stile or rail V 5; the edges of 60 the V member 12 being bent inwardly toward the body of the socket and thence outwardly and backwardly to form a recess 13, and lip 14. By forming the socket 11 of about the same width as the channel 70 4, the socket may be projected through the channel by springing the neck members 8 backwardly, if necessary, so that the stile or rail V's may be projected into the recess 13 and against the free edges of the socket 75 11, the free edges of the socket being sprung outwardly to allow the free edges of the stile or rail to enter beneath hooked portions 15 and lock thereagainst to hold the socket to the stile or rail. It is apparent that with 80 the socket in place the panel 16 may be set with its edge within the socket 11.

In order to enhance the appearance of the door, I prefer to provide the panel with a molding 17, which is adapted for coöperative engagement with the panel socket, so 85 that it may be applied to the door or panel without the aid of screws or bolts. In accomplishing this object I provide the molding with a flange 18 which is adapted to 90 bear against the face of the panel; and at its opposite edge with a keeper flange 19, which is adapted for projection between the inturned portion 7 of the stile or rail and the V-shaped lip 14 of the panel socket, so that 95 the molding V may rest within the recess 80 beneath the socket V, and be locked securely in place. It is apparent that a molding of this construction may be easily and quickly applied to the door after the panel 100 is in place, and that when so applied it will be held securely to the stile or rail and to the panel, although it may be removed by springing the parts reversely from the setting action.

When the door panel is to be installed after the body of the door is completed, I modify the construction by turning the outer edge of the molding member inwardly and offsetting the same from a shelf 21 (Fig. 110 VI) for carrying the panel, the extreme edge of the shelf being provided with a

spring lip 22, which is adapted to overlie the socket V 12, to hold the parts firmly in position. With this construction the opposite molding member bears against the 5 panel the same as in the preferred construction.

In assembling a metal door equipped with my improvements, the socket members are applied to the individual stiles and rails, 10 and three of the members assembled, leaving an open end for the insertion of the panel. The panel is then placed in the sockets of the three members and the fourth member connected with the other three to completely 15 inclose the panel. The molding is then applied to the socket members on opposite sides of the panel to complete the structure.

When a panel is to be applied where the doors is to be erected, as when a glass panel 20 is used, the molding at one side of the door is installed at the factory and the molding at the opposite side applied after the glass panel has been placed. In both cases panel sockets are placed in the stiles or rails by 25 projecting the necks 11 through the channels of the stiles and rails, and forcing the keeper lips of the V hooks on the stiles and rails inwardly until the latter have been seated within the keeper recess and locked 30 against the hook members 15 on the socket V's, the corners of the panel sockets being cut away in order that all of the sockets may be installed as described.

After the panel has been placed, the molding 35 may be applied by forcing the V keepers 19 between the inturned members 7 of the stiles and rails so the V lips 14 of the panel sockets will hold the keeper members within the recess 20, the resiliency of the metal 40 allowing the parts to be placed, and holding the same in position after they have been set, so that the molding will lie closely against the door panel. It is also apparent that, when desired, the molding having the 45 panel seat may be used, so that the edges of

the panel may be carried up the molding seats rather than in the socket seats, this arrangement, however, making no change in the manner of assembling the parts.

Having thus described my invention, what 50 I claim as new therein, and desire to secure by Letters-Patent, is:—

1. A metal door comprising a body member having a contracted neck at one edge with the sides of the neck turned back at 55 their free edges to form V-shaped, yieldable keepers, and a socket member comprising a U-shaped body adapted to seat within said neck and having its free edges turned back to form V-shaped members, and having in- 60 turned hook portions at their free edges adapted to compress the body lips when the socket is projected within the neck and for holding against the edges of said lips when the latter have returned to normal position. 65

2. A metal door comprising a body member having a contracted neck at one edge with the sides of the neck turned back at 70 their free edges to form V-shaped, yieldable keepers, a socket member comprising a U-shaped body adapted to seat within said neck and having its free edges turned back to form V-shaped members, and having in- 75 turned hook portions at their free edges adapted to compress the body lips when the socket is projected within the neck and for holding against the edges of said lips when the latter have returned to normal position, and molding members having keeper flanges adapted for projection between the socket 80 hooks and the body of the door to retain said molding members in position and cover the socket.

In testimony whereof I affix my signature in presence of two witnesses.

SVEN G. BOLIN.
